INVENTOR:

Richard H. Oates,
BY John Algedersheim ATTORNEY.

UNITED STATES PATENT OFFICE.

RICHARD H. OATES, OF PORT CLINTON, PENNSYLVANIA.

PUDDLING-FURNACE.

SPECIFICATION forming part of Letters Patent No. 293,770, dated February 19, 1884.

Application filed February 8, 1883. (No model.)

To all whom it may concern:

Be it known that I, RICHARD H. OATES, a citizen of the United States, residing at Port Clinton, in the county of Schuylkill, State of Pennsylvania, have invented a new and useful Improvement in Puddling-Furnaces, which improvement is fully set forth in the following specification and accompanying drawings, in which—

10 Figure 1 is a front elevation, partly sectional in line x x , Fig. 2, of the puddling-furnace embodying my invention. Fig. 2 is a vertical section in line y y , Fig. 1. Fig. 3 is a horizontal section of a portion in line z z , Fig. 1.

Similar letters of reference indicate corresponding parts in the several figures.

My invention relates to improvements in puddling-furnaces; and it consists of a chamber having circular reciprocating motions.

It also consists of shoes which depend from the puddling-chamber and support the same.

It further consists of means for closing the joints on opposite sides of the chamber, respectively, with the furnace and flue.

It further consists of certain other details of construction, as will be hereinafter set forth.

Referring to the drawings, A represents a puddling-chamber, which is supported by 30 means of segmental shoes B, which are secured to and depend from the under side of said chamber, and mounted on rollers C, whose bearings are on a suitable saddle or base, D; said rollers being arranged in a curvilinear direction. (See Fig. 2.)

E represents a furnace, and F represents a flue, which furnace and flue are properly supported on opposite sides of the chamber A, and communicate therewith, as at a.

40 On each side of the center of the chamber A is a hollow trunnion, G, which is cast with or secured to said chamber and abuts against a boss, H, the bosses being respectively secured to the adjacent inner ends of the furnace E and flue, the periphery of each trunnion and boss being flanged, so as to be embraced by a flanged annulus, J, whereby the trunnion and boss of each side are kept close together, and the joint between said parts is

45 50 kept tight.

K represents a rotary reciprocating shaft, which is mounted on standards L, and has connected to it cross-heads M, to the ends of which are pivoted arms N, whose lower ends are pivoted to the ends of the chamber A.

55

To the shaft K is secured a cross-head, P, which, through the medium of arms, crank-shafts, and gearing, receives motion from the pulley Q, to which power is communicated in any suitable manner.

60

In the chamber A, at each corner thereof, is a diagonal block or lining, R, and in one or each end opening of said chamber is a vertical bridge, S, which thus divides said opening or openings. (See Figs. 2 and 3.)

65

The fire is maintained in the furnace and the puddling-chamber supplied with metal, as usual. Power is applied to the pulley Q, the effect of which is to cause, by means of the intervening mechanism, the reciprocation of 70 the puddling-chamber, the motion of which is curvilinear or circular, whereby the mass of metal is forced from end to end of said chamber and deflected inwardly at said ends, owing to the diagonal corner-blocks R R, these actions causing the proper puddling of the metal, it being noticed that owing to the curvilinear motion of the chamber the molten mass of metal is uniformly directed backward and forward along the floor of the chamber in between the blocks R R. As the bridges S move with the chamber, the flames from the furnace are deflected by the varying positions of the bridges, and their directions thereby constantly changed, so that the action of the fire 85 on the metal is thorough and uniform.

Having thus described my invention, what I claim as new, and desire to secure by Letters Patent, is—

1. The furnace E and flue F, each with a 90 boss, H, in combination with an intermediate puddling-chamber, A, having segmental shoes B, and a saddle, D, with rollers C, said chamber having on its inner corners deflectors R, and at opposite ends divisional 95 bridges S and hollow trunnions G, substantially as set forth.

2. The furnace E and flue F, each with a boss, H, in combination with an intermediate puddling-chamber, A, having segmental shoes 100

B, flanged annuli J, and a saddle, D, with rollers C, said chamber having interior deflectors, R, and at opposite ends divisional bridges S and hollow trunnions G, having flanges which are embraced by the flanged annuli J, substantially as set forth.

3. The furnace E and flue F, each with a boss, H, in combination with an intermediate puddling-chamber, A, having segmental shoes

B, divisional bridges S, deflectors R, hollow trunnions G, the saddle D, with rollers C, the annuli J, shaft K, cross-heads M, arms N, cross-head P, and operating mechanism, substantially as and for the purpose set forth.

RICHARD H. OATES.
